UNITED STATES PATENT OFFICE

153,979

DESIGN FOR A TOY BIRD

Delmar J. Ranahan, Wilmington, Calif.

Application December 30, 1947, Serial No. 143,450

Term of patent 14 years

(Cl. D34—2)

To all whom it may concern:

Be it known that I, Delmar J. Ranahan, a citizen of the United States of America, residing at Wilmington, in the county of Los Angeles and State of California, have invented a new, original, and ornamental Design for a Toy Bird, of which the following is a specification, reference being had to the accompanying drawing forming a part thereof wherein:

I claim:

The ornamental design for a toy bird, as shown.

DELMAR J. RANAHAN.
